UNITED STATES PATENT OFFICE.

WILLIAM HORACE SODEAU AND VICTORY PURDY FRANCOMBE, OF ST. TROPEZ, VAR, FRANCE, ASSIGNEES TO THE WHITEHEAD TORPEDO WORKS (WEYMOUTH) LIMITED, (IN LIQUIDATION), OF WEYMOUTH, ENGLAND, A BRITISH COMPANY.

AUTOMOBILE TORPEDO.

1,401,288.

Specification of Letters Patent. Patented Dec. 27, 1921.

Application filed October 5, 1921. Serial No. 505,671.

To all whom it may concern:

Be it known that we, WILLIAM HORACE SODEAU and VICTORY PURDY FRANCOMBE, both subjects of the King of Great Britain, and both residing at St. Tropez, (Var) France, have invented certain new and useful Improvements in or Relating to Automobile Torpedoes, of which the following is a specification.

10 This invention relates to automobile torpedoes and has for its chief object to provide an improved device for insuring that the torpedo shall acquire ample positive buoyancy at the end of a practice run, so 15 that it may be readily picked up. Such devices have become necessary on account of the great negative buoyancy possessed by modern torpedoes coupled with the desirability of making practice shots under the 20 same conditions of trim and buoyancy as those obtaining in war shots, which necessitates the use of an exercising or practice head of the same weight as the war head.

It is customary to employ a practice head 25 filled with water or other liquid, herein called the "ballast", which is ejected or blown out after the conclusion of the run by means of compressed air or other gas, herein referred to as "air". In the known methods 30 the air for blowing out the ballast is released on the fulfilment of some predetermined condition such as (a) the decrease of the pressure produced on a member by the movement of the torpedo through the water, 35 or (b) the attainment of a certain pressure on a hydrostatic valve or the like due to the torpedo sinking to a depth which necessarily must markedly exceed its normal running depth. Known devices based upon the 40 first condition mentioned are liable to blow out the ballast in the event of the torpedo "breaking surface" and are difficult to adjust satisfactorily in the case of a torpedo which can be so set as to be shot at more than one speed, inasmuch as if the device operates satisfactorily at a low speed it is apt to act too late at high speeds so that the torpedo may strike the bottom before the ballast has begun to be blown out; devices based upon 50 the second condition mentioned are apt to blow out the ballast during the initial drive of the torpedo and to fail to act in the event of the shot terminating in water of insufficient depth.

According to the present invention we 55 provide means for effecting the change from negative buoyancy to positive buoyancy only when two distinct conditions based upon the speed and depth of the torpedo occur at one and the same time, *e. g.* only when the pressure produced on a member by the movement of the torpedo has fallen below a predetermined limit (which limit may, if desired, be made to vary automatically or otherwise according to the speed at which the 60 torpedo runs in any given shot) and when, simultaneously, the depth of the torpedo is not less than a predetermined amount which is hereinafter termed the "blowing depth" and which is preferably less than the normal 65 running depth of the torpedo. For this purpose the release valve for the air used to blow out the ballast is placed under the dual control of the aforesaid pressure operated member and a hydrostatic valve or its equivalent 70 in such a manner that neither the movement of the said member that occurs when the pressure to which it is subjected falls below the predetermined limit (this resulting either 75 from a diminution in the speed of the torpedo or from the torpedo "breaking surface") nor the movement of the hydrostatic valve that occurs when the torpedo sinks below the predetermined blowing depth, will 80 by itself open the air release valve, this opening taking place only when the effects of both the said movements occur at the same time. The pressure operated member affected by the motion of the torpedo through the water may conveniently take the well known 85 form of one or more whiskers, pivoted flaps or sliding plates arranged so as to be pressed back, against the force exerted by an appropriate spring or springs, to an extent depending on the velocity of the torpedo 90 through the water. After the said spring has been compressed, extended or otherwise energized to a predetermined extent, the improved arrangement (herein termed the pistol) becomes "cocked" so that during the 95 subsequent deenergization of the spring owing to the reduction of the pressure on the said member, the said spring carries forward a spindle or the like which is adapted to become mechanically connected to the air 100 release valve preferably by means of a ratchet or rack member or similar device arranged so that the first tooth can be en-

- gaged in consequence of the travel produced in a low speed shot whereas shots at high speeds produce engagement farther along so that the final cocking takes place under 5 conditions approximating to the maximum speed in the particular shot; in this manner a moderate reduction of speed causes the valve to be actuated thereby avoiding undue postponement of the blowing of the ballast.
- 10 As already seen, a pistol of the above nature would cause the ballast to be blown on the torpedo breaking surface. Attempts have been made to prevent this by means of delay arrangements, *e. g.*, an oil bottle inserted between 15 the air bottle and the air release valve so that a quantity of oil must be forced through a small passage before the air can be released. This expedient has, however, proved unsatisfactory as the delay is relatively short unless the passage is reduced to a point at which it causes undesirable delay in emptying the head. We therefore connect the pistol to the air release valve in conjunction with the hydrostatic valve in such a 25 way that no blowing of the ballast can take place unless the torpedo is submerged to at least a predetermined blowing depth. On the other hand the hydrostatic valve cannot cause the ballast to be blown without the co- 30 operation of the pistol.
- In order that the said invention may be clearly understood and readily carried into effect the same will be more fully described with reference to the accompanying drawings, in which:—
- 35 Figures 1, 2 and 3 are sectional side elevations showing more or less diagrammatically (and in three different positions hereinafter referred to) one form of our improvements.
- 40 Figs. 4, 5 and 6 are views similar to Figs. 1, 2 and 3 showing another form of our improvements.
- 45 Figs. 7, 8 and 9 are sections showing diagrammatically certain parts of Figs. 4, 5 and 6 in different positions hereinafter referred to, and
- 50 Figs. 10 and 11 are sectional side elevations showing two further forms of our improvements.
- 55 In the various figures of the drawings A is the shell of the practice head of the torpedo, A' is the air reservoir arranged in the head and A² is the air release valve which, when moved from its seat, admits compressed air from the air reservoir A' into the head through the port a² to discharge the liquid ballast therefrom in the known manner. In the examples shown an oil bottle or chamber a' is disposed between 60 the air reservoir A' and the valve A² as is well understood for the purpose of preventing leakage of air from the said reservoir. B is the aforesaid pressure operated member affected by the motion of the torpedo through the water, this member in Figs. 1, 2, 3, 10 and 11 taking the form of a spring-controlled sliding plate disposed in a cavity or recess B' open to the external water and in Figs. 4, 5 and 6 taking the form of a spring controlled flap projecting beyond the 70 surface of the torpedo head. C is the movable element of the aforesaid hydrostatic valve which element may consist of a flexible diaphragm (Figs. 1 to 6 and 10) or a piston (Fig. 11) which in either case closes 75 a chamber C' and is subjected on one side to the pressure of the external water and on the other side to the pressure of a spring C² and of the air confined in the chamber C' as in the customary forms of hydrostatic valve 80 used in the depth-keeping mechanism of torpedoes.
- 85 Referring to Figs. 1 to 3, the sliding plate B has a rod b suitably guided in fixed disks b', b' and provided with rack teeth b², b² with which a spring controlled pawl B² is adapted to engage. The said pawl and rod (together with their associated parts) constitute the aforesaid "pistol." The rear end of the pawl B² is pivoted to the upper end of a floating lever B the lower end of which is adapted to operate, through a two armed lever B⁴, on the stem of the aforesaid valve A². The said floating lever B³ is pivoted at 90 b³ to a rod C⁴ moving with the aforesaid flexible diaphragm C and this lever and the upper arm of the lever B⁴ are disposed in a chamber b⁴ which is open at its upper end to the external water, the lower arm of the lever B⁴ being situated outside this chamber 95 and connected to the upper arm by an axis pin which passes through a gland bearing in one of the side walls of the chamber b⁴. When the torpedo has been launched one or other of the rack teeth b², b² (depending upon the pressure of the water on the plate B which pressure in turn depends on the speed of the torpedo) will engage with the pawl B² as shown and the diaphragm C of the hydrostatic valve will be pressed inward, this being the position shown by Fig. 1. When the torpedo "breaks surface" the spring of the plate B will move the latter forward carrying with it the pawl B². The diaphragm C of the hydrostatic valve will at 100 the same time move outward, with the result that the floating lever B³ will occupy the position shown by Fig. 2. If when the torpedo is running at a depth not less than the aforesaid blowing depth (which corresponds to a position of the disk C at some predetermined point between the positions it occupies in Figs. 1 and 2) the plate B should move forward as a result of the diminution in speed which occurs near the end of the run, the floating lever B³ will be moved into the position shown by Fig. 3 and operates to open the valve A² to admit air from the reservoir A' into the head as aforesaid. The movements of the floating lever B³ are limited 110

- 130

ited by suitable stops b^{3x} , b^{3x} and a relief passage b^{4x} is provided behind the plate B to avoid an accumulation of water in the recess B' behind this plate which might prevent rearward movement of the latter.

In the construction shown by Figs. 4 to 6, the lever B⁸ instead of being floating and pivoted to the rod C^x moving with the diaphragm C of the hydrostatic valve, is pivoted at a fixed point b^8 and is disposed between the said rod C^x and a plunger or other member b which corresponds to the rod b of Figs. 1 to 3. In this arrangement the force exerted by the spring C² of the hydrostatic valve is opposed by the force exerted by the plunger b (which is suitably interconnected in the manner described later, with the flap B operated by the pressure of the water during the passage of the torpedo therethrough) so that the said plunger cannot operate the levers B³ and B⁴ to move the valve A² from its seat unless there is a certain pressure (namely that obtaining at the aforesaid "blowing depth") acting on the hydrostatic valve to wholly or partially counteract the effect of the spring C² and move the rod C^x clear of the lever B³ as shown by Fig. 6. Figs. 4, 5 and 6 show the various parts of this arrangement in the position they occupy under conditions similar to those described with reference to Figs. 1, 2 and 3 respectively. The flap B may be sliding as it may be pivoted at its inner end.

In Figs. 7, 8 and 9 which show the connections between the flap B and the member b of Figs. 4, 5 and 6 the flap is pivoted and is connected to a sleeve B⁵ disposed in a fixed casing B⁶ with a compression spring b⁶ interposed. This sleeve B⁵ has a transverse partition b⁵ having a slot through which a plate b⁷ on the rod of the member b can pass when the rod is turned to bring the plate into coincidence with the said slot. The upper end of the said rod has a head b⁸ by which it can be angularly displaced against the resistance of a torsion spring B⁸. In operation the arrangement works as follows:— Assuming the parts to be in the position shown in Fig. 9 which they occupy at the end of a run, they are re-set by turning the head b⁸ against the resistance of the torsion spring B⁸ (which is under compression) until the plate b⁷ registers with the slot in the partition b⁵, whereupon the said spring moves the plate b⁷ and the parts connected thereto into the position shown by Fig. 7 ready for the next run. During the run the flap B is forced back into the position shown in Fig. 8, thereby raising the sleeve B⁵, compressing the spring b⁶ and moving the partition b⁵ so that its slot comes clear of the plate b⁷ which is then angularly displaced by the torsion spring B⁸ into the position shown by Fig. 8 in which the said

plate bears against the under side of the partition b⁵; during this operation the member b is prevented from following the sleeve B⁵ owing to the fact that the said member bears against the casing B⁶. When the torpedo stops the parts will occupy the position shown by Fig. 9 in which the member has been forced downward to operate the lever B³ of Figs. 4, 5 and 6 and so open the valve A² as aforesaid.

In the construction shown by Fig. 10 the arrangement of the pistol is similar to that of Figs. 1 to 3 except that the rod b provided with the rack teeth b², b² is pivotally connected to the plate B and is forced into engagement with the part B^x of the member B² by a spring B^{2x} on the latter. In this construction the rod C^x of the hydrostatic valve operates to rock the member B² about its pivotal connection with a link b^{2x} (which is pivotally connected to a lever B³ operating upon the valve A²) so as to bring a projection B⁰ on this member in line with and behind a stop-piece A⁰ when the torpedo is running at less than its "blowing depth." In this condition of affairs the valve A² cannot be opened in the event of the torpedo "breaking surface." In an alternative arrangement the rod C^x instead of operating on the member B², might operate upon a movable stop to displace the latter into and out of the path of a projection on the said member in accordance with the depth at which the torpedo is running.

In the construction shown by Fig. 11 the arrangement of the pistol is similar to that of Figs. 1 to 3, but the rod C^x of the hydrostatic valve operates to uncock the pistol (i. e. to temporarily disconnect the pawl B² from the rod b) when the torpedo is running at less than its "blowing depth." For this purpose the rod C^x is connected as shown to the pawl B² through the intermediary of a spring b⁰ controlling the pawl.

In the forms of pistol herein described the position of the pawl B² (or its equivalent) and the rack member b may be reversed; alternatively the part B² may be in the form of a rack member the teeth of which engage with those of the rack member b.

We wish it to be understood that we do not desire to limit the herein described pistols to their employment in conjunction with the hydrostatic valve (or its equivalent) as the former may be used without the latter in cases where the blowing out of the ballast is wished to be made dependent only on a reduction in the speed of the torpedo; also that we do not desire to limit the herein described invention to the employment of the pistols hereinbefore described as pistols of other constructions, if desired, may be used.

We also wish it to be understood that

- although the invention has been described in its application to the method of changing the negative buoyancy to positive buoyancy by blowing out liquid ballast it can if desired be employed in conjunction with other methods such as that involving the release of solid ballast (in which case the air release valve would be replaced by one or more catches or other suitable releasing means)
- 10 and that involving the use of an extensible or telescopic head in which case the air release valve would be used in conjunction with suitable catches or the like.

A device which causes the conversion from negative buoyancy to positive buoyancy to occur after the lapse of a given time, *e. g.* one actuated by clock work or one coming into action after a plug of salammoniac or other soluble material has become dissolved,

20 may be employed in conjunction with the above described arrangements in order to insure the final flotation of the torpedo in the event of the other arrangements becoming damaged or inoperative.

25 What we claim and desire to secure by Letters Patent of the United States is:—

1. In an automobile torpedo, the combination with means for changing from normal negative buoyancy to positive buoyancy at the end of a practice run, of means whereby said change is permitted to occur only when two distinct conditions based upon the speed and depth of the torpedo exist at one and the same time.
- 35 2. In an automobile torpedo, the combination with means for changing from normal negative buoyancy to positive buoyancy at the end of a practice run, of a device movable under the influence of the speed of the
- 40 torpedo during the run, a device movable under the influence of the depth of the torpedo and means whereby said devices are permitted to operate upon the buoyancy changing means only when the speed of the
- 45 torpedo falls below a predetermined limit and when at the same time the depth of the torpedo is not less than a predetermined amount.

3. In an automobile torpedo, the combination with a device for controlling the buoyancy of the torpedo so as to change from normal negative buoyancy to positive buoyancy at the end of a practice run, of a member movable in accordance with the speed of the torpedo during the run, a member movable in accordance with the depth of the torpedo, and means interposed between said members and said device whereby the latter is operated to effect the change from negative buoyancy to positive buoyancy only when said members both occupy predetermined positions at the same time.
- 55 4. In an automobile torpedo, the combination with a device for controlling the

from normal negative buoyancy to positive buoyancy at the end of a practice run, of a spring controlled member so arranged in contact with the surrounding water as to be operated by the pressure due to the passage of the torpedo through the water, a spring controlled member so arranged in contact with the water as to be moved by static pressure due to the depth of the torpedo beneath the surface of the water and means interposed between said members and said device whereby the latter is operated to effect the change from negative buoyancy to positive buoyancy only when said members both occupy predetermined positions at the same time.

5. In an automobile torpedo, the combination with a device for controlling the buoyancy of the torpedo so as to change from normal negative buoyancy to positive buoyancy at the end of a practice run, of a spring controlled member so arranged in contact with the water as to be moved by static pressure due to the depth of the torpedo beneath the surface of the water and a lever interposed between said members and said device whereby the latter is operated to effect the change from negative buoyancy to positive buoyancy only when said members both occupy predetermined positions at the same time.

6. In an automobile torpedo, the combination with a device for controlling the buoyancy of the torpedo so as to change from normal negative buoyancy to positive buoyancy at the end of a practice run, of a spring controlled member so arranged in contact with the surrounding water as to be operated by the pressure due to the passage of the torpedo through the water, a spring controlled member so arranged in contact with the water as to be moved by static pressure due to the depth of the torpedo beneath the surface of the water and a floating lever arrangement interposed between said members and said device whereby the latter is operated to effect the change from negative buoyancy to positive buoyancy only when said members both occupy predetermined positions at the same time.

7. In an automobile torpedo, the combination with a practice head normally filled with liquid ballast, of a valve for controlling the admission of compressed air to said head for forcing out the liquid ballast so as to change from normal negative buoyancy to positive buoyancy at the end of a practice run, a device movable under the influence of the speed of the torpedo during the run, a device movable under the influence of the depth of the torpedo and means whereby

said devices are permitted to operate upon said valve only when the speed of the torpedo falls below a predetermined limit and when at the same time the depth of the torpedo is not less than a predetermined amount.

8. In an automobile torpedo, the combination with a practice head normally filled with liquid ballast, of a valve for controlling the admission of compressed air to said head for forcing out the liquid ballast so as to change from normal negative buoyancy to positive buoyancy at the end of a practice run, a member movable in accordance with the speed of the torpedo during the run, a member movable in accordance with the depth of the torpedo, and means interposed between said members and said valve whereby the latter is operated to effect the change from negative buoyancy to positive buoyancy only when said members both occupy predetermined positions at the same time.
9. In an automobile torpedo, the combination with means for changing from normal negative buoyancy to positive buoyancy at the end of a practice run, of a member movable in accordance with the speed of the torpedo during the run, and means whereby said member becomes connected to the buoyancy changing means at different points dependent upon the maximum speed attained by the torpedo in any particular run.
10. In an automobile torpedo, the combination with means for changing from normal negative buoyancy to positive buoyancy at the end of a practice run, of a spring controlled member operated by the pressure due to the passage of the torpedo through the water and means whereby said member

becomes connected to the buoyancy changing means at different points dependent upon the maximum speed attained by the torpedo in any particular run.

11. In an automobile torpedo, the combination with a practice head normally filled with liquid ballast, of a valve for controlling the admission of compressed air to said head for forcing out the liquid ballast so as to change from normal negative buoyancy to positive buoyancy at the end of a practice run, mechanism for operating said valve, a member movable in accordance with the speed of the torpedo and means whereby said member becomes automatically connected to the said mechanism at different points dependent upon the maximum speed attained by the torpedo in any particular run.

12. In an automobile torpedo, the combination with a practice head normally filled with liquid ballast, a valve for controlling the admission of compressed air to said head for forcing out the liquid ballast so as to change from normal negative buoyancy to positive buoyancy at the end of a practice run, a floating lever for operating said valve, a member movable in accordance with the depth of the torpedo, said member operating on said lever, a member movable in accordance with the speed of the torpedo and means whereby the last mentioned member becomes automatically connected to said lever at different points dependent upon the maximum speed attained by the torpedo in any particular run.

WILLIAM HORACE SODEAU.
VICTORY PURDY FRANCOMBE.
